(57) **CLAIM**

I claim the ornamental design for an automobile wheel, as shown and described.

DESCRIPTION

FIG. 1 is a front elevational view of an automobile wheel according to the claimed design; and,

FIG. 2 is a perspective view of the automobile wheel according to the claimed design.

The broken line showing of the rear of the rim is included for the purpose of illustrating environmental subject matter and forms no part of the claimed design.

1 Claim, 2 Drawing Sheets

FIG.1

FIG. 2
